UNITED STATES PATENT OFFICE.

HENRY J. REEDY, OF CINCINNATI, OHIO.

ELEVATOR.

SPECIFICATION forming part of Letters Patent No. 325,971, dated September 8, 1885.

Application filed September 8, 1884. (No. model.)

To all whom it may concern:

Be it known that I, HENRY J. REEDY, a resident of Cincinnati, in the county of Hamilton and State of Ohio, have invented certain new and useful Improvements in Elevators, of which the following is a specification.

My invention relates to the mechanism for opening and closing the valve to stop and start the elevator.

10 The object of my invention is to provide suitable mechanism for opening and closing the valves slowly, so as to avoid the shock and jar incident to the stopping and starting of the hydraulic elevators. It consists in connecting the 15 stopping and starting pulley with the valves by gear devices intermediate between the shifting-pulley and the valve, so arranged as to have the valve-pulley move at a relatively slower speed than the shifting-pulley, all of which will be 20 fully set forth in the description of the accompanying drawings, forming a part of this specification, in which—

Figure 1 is a front elevation of my improvement applied to an elevator. Fig. 2 is a side 25 elevation of the same; Fig. 3, a top plan view of the gear devices. Fig. 4 is a longitudinal sectional view of the valve-cylinders and frame, and Fig. 5 a top plan of the same.

A represents the cab; B, ordinary side 30 guide-posts; C, the main driving-pulley over which the cable a winds to raise and lower the cab A.

I have not shown the connecting mechanism of the pulley C with the main driving devices 35 operated by the hydraulic motor, as these may be of any well-known form of construction.

D represent the shifting-pulley, over which the cable E is wound in the ordinary manner.

F represents a sheave, and G a weight for 40 keeping the cable stretched taut. This is an important feature, as it automatically takes up the stretch of the cable. The movement of cable E drives pulley D in one direction, say, for opening the valve, and the reverse 45 movement of cable E closes the valve.

In order that the movement of the valve in opening and closing may be gradual, so as to avoid the jars occasioned by suddenly introducing or cutting off of the supply of water, 50 I employ gearing-back devices intermediate between the shifting-pulley D and the valve-pulley H.

I represents a shaft on which the pulley D is keyed.

J represents a pinion keyed likewise upon 55 shaft I.

K represents a much larger spur-wheel meshing with pinion J, so as to gear back the movement of shaft L, which carries pulley M.

M represents a sheave over which cable N passes, and thence around the valve-pulley H.

By this arrangement of the shafts I L and transmitting gear J K the speed of pulley D and cable E is much greater than the speed of the secondary cable N and valve-pulley H; 65 hence the cable E must be moved by the operator riding on the cab A a considerable distance before the valve-pulley H is moved a sufficient distance to open or close the valve; hence the cab A is started and stopped slowly 70 by the operator without occasioning any shock or jar. This is very important, not only in the operation of the cab for the ease and comfort of the passengers, but it is very important in obviating danger of breaking the machinery by the shocks or water-hammer, which 75 is entirely avoided by my slowing devices, which also obviates the bursting of the pipes and other breakages that are of common occurrence in the ordinary sudden mode of opening and closing the valve on hydraulic elevators in common use.

Referring to Figs. 4 and 5, the numerals 1 2 represent the two valve-cylinders; 3, induction port; 4, eduction port or pipe. 5 represents, say, the starting-valve; 6, the stopping-valve. 7 7 represent inlet-ports to the cylindrical valve 5, which, when raised in the position shown in Fig. 4, allows water to be discharged in pipe 8.

From thence it passes out 90 pipe 9 into the piston-chamber of the main driving-piston. Valve 6 being closed, the force of the water is exerted upon the driving-piston.

10 represents the valve-frame mounted on the cylinders 1 2. H represents the 95 valve-pulley, journaled to the frame or plate 10. 11 represents a spur-gear on shaft 12.

13 represents the rack on rod 14. 15 represents inclines on rod 14, which passes through slot 16 in the valve-stems 17, and raises and lowers the valves 5 and 6. As shown in Fig. 4, piece 15 has raised valve 5 off its seat, and the water is passing into the cylinder. When shaft 14 is reciprocated in the opposite direc-

tion, valve 5 is closed, valve 6 is raised, and the weight of the elevator, acting upon the cylinder, discharges the water out through valve 6 and escape 4.

5 Having described my invention, what I claim is—

1. In a hydraulic elevator, the combination, with a cab, A, of a main cable, E, connecting therewith, a secondary cable, N, connecting with a valve, and intermediate back gear connecting with said cables for moving cable N at a slower speed than cable E, substantially as described.
- 10 2. In a hydraulic elevator, the combination

of cable E, shifting-pulley D, around which 15 said cable passes, pulley I and valve-pulley H, cable N, connecting said pulleys I and H, and gears J and K, of varying diameters and connecting with pulleys D and L, to move cable N at a slower speed than E, substantially 20 as described.

In testimony whereof I have hereunto set my hand.

HENRY J. REEDY.
